UNITED STATES PATENT OFFICE.

GEORGE DORROS, OF NEW YORK, N. Y.

DESIGN FOR A DECORATED BOX.

Application filed February 28, 1923. Serial No. 5,320. Term of patent 14 years.

To all whom it may concern:

Be it known that I, GEORGE DORROS, a citizen of the United States, and a resident of New York city, county of New York, and State of New York, have invented a new and original Design for a Decorated Box, of which the following is a specification, reference being had to the accompanying drawing, forming part thereof.

My design appears upon the fabric of the box.

I claim:

The ornamental design for a decorated box, as shown.

GEORGE DORROS.
